UNITED STATES PATENT OFFICE.

CHESTER HUNT, OF LYNN, MASSACHUSETTS, ASSIGNOR TO UNITED SHOE MACHINERY CORPORATION, OF PATERSON, NEW JERSEY, A CORPORATION OF NEW JERSEY.

LAST AND DEVICE FOR ATTACHING HEELS.

1,399,772.

Specification of Letters Patent. Patented Dec. 13, 1921.

Application filed April 7, 1919. Serial No. 287,972.

To all whom it may concern:

Be it known that I, CHESTER HUNT, a citizen of the United States, residing at Lynn, in the county of Essex and State of Massachusetts, have invented certain Improvements in Lasts and Devices for Attaching Heels, of which the following description, in connection with the accompanying drawings, is a specification, like reference characters on the drawings indicating like parts in the several figures.

The present invention relates to making shoes and especially to the attachment of heels to shoes.

15 The process of attaching heels known as inside nailing usually necessitates re-lasting. That is, the shoe is partly made upon a last, then separated therefrom and the heel attached, and then replaced upon the same last or upon a different one for subsequent operations. The necessary operations of withdrawing the last and re-lasting involve considerable time and labor and also frequently cause injurious strains upon the shoe. To 25 avoid entire removal of a last it has heretofore been proposed to use lasts having separable fore and heel parts and to remove the heel part to make room for elements of a heel machine and then re-insert said heel part after the inside nailing of the heel has 30 been effected. An objection to this, however, is not only the time and labor involved but also the reduction of the lasting pressure and the slackening up of the longitudinal 35 tension of the shoe at a time when the materials of the shoe have not become permanently set to the shape of the last.

The present invention provides for using the heel seat portion of a last as an element of heeling mechanism in such manner that the lasting tension of the shoe is unaffected. An advantage of the illustrated construction and arrangement is that the heeling nails can be driven through as close to the margin 45 of the heel as desired whatever the width and length of the heel.

In another aspect, my present invention contemplates the partial making of a shoe upon a last, then displacing the cone of the 50 last and driving heeling nails through the heel seat portion of the last and then continuing the making operations, all without disturbing the lasting tension of the shoe.

An important feature of my invention 55 consists in a last having a cone portion

which may be displaced, leaving a heel seat portion which will retain the shoe under lasting tension, said heel seat portion being constructed and arranged to permit heeling nails to be driven through it from the inside 60 of the shoe.

To facilitate such use of the last and at the same time to facilitate ready separation of the shoe and last subsequently, the illustrated last has a plurality of heel sections 65, each of which is hinged to the forepart so that one may be displaced to permit heel attaching nails to be driven through the other, while the other part also may be swung upwardly preliminarily to pulling 70 the last.

Other objects and features of the invention will be apparent from the following description when considered in connection with the accompanying drawings and the 75 novel features of the invention will be pointed out in the claims.

Figure 1 of the drawings is a side elevation of my improved last, with a dotted line indication of the position occupied by the cone 80 during the inside nailing operation;

Fig. 2 is a perspective view of the heel part sections of the last, the cone section being broken out;

Fig. 3 is a sectional elevation of the last, 85 with a shoe thereon, and with the parts of the nailing mechanism in the positions which they occupy at the completion of the nail driving.

Fig. 4 is a perspective view, partly in section, of the nailing mechanism and the lower heel section of the last, in the relative positions which they occupy when the nails are being fed to position in the holes of said heel section of the last. 95

In the illustrated embodiment of the invention, the last comprises a forepart 12 which is usually made of wood, said forepart carrying a pin 13 upon which is mounted a somewhat disk-shaped lug 14 of the 100 section 15 of the heel part. The cone section 16 of the heel part of the last has a rib or plate 17 which terminates in a somewhat disk-shaped lug 18 mounted on the pivot or hinge pin 13, said plate 17 being 105 fitted in a recess of the cone 16 and secured therein by suitable means such as transverse pins 19.

The cone 16 and the heel seat section 15 have suitable coöoperating devices to prevent 110

lateral displacement of one relatively to the other, such devices being illustrated as comprising dowels 20 projecting from the cone 16 to engage sockets 21 in the section 15.

- 5 The sections 15, 16 are divided on a substantially horizontal line, the plane of the line of division being preferably at substantially the greatest width of the heel part of the last so that the section 15 will transversely and longitudinally fit the lower heel seat portion of the shoe whereby said section 15 has an area ample to enable the nail holes 22, the object of which will be presently described, to be formed so near the margin of 10 the section 15 that nails passing in parallel relationship through the holes 22 will enter those portions of a heel substantially the same as has heretofore been customary when inside nailing is performed after removal 15 of a last as hereinbefore described.

The hinge connection between the forepart 12 and the sections 15, 16 is such as to enable the cone section 16 to be swung up, substantially as indicated by dotted lines 20 in Fig. 1 and full lines in Fig. 3, far enough to enable the portions of a heel nailing mechanism, presently to be described, to be inserted past the section 16. To enable heel-nailing nails to be first deposited or inserted in 25 the holes 22 and then driven down into a heel, I employ such mechanism as is illustrated in Figs. 3 and 4. Said mechanism comprises a nail guide block 23 carried by the lower end of a suitably actuated plunger 24, the block 23 having dowels 25 relatively spaced the same as the dowels 20 of the cone 16 so that, when the block 23 is brought into relationship with the heel section 15 of the last, as shown in Figs. 3 and 30 4, the said dowels 25 will enter the sockets 21 of the heel section 15 to render it certain that the nail throats 26 in said block 23 will be in accurate alignment with the holes 22.

Communicating with the throats 26 are 35 branches 27 through which nails are supplied as presently described. A driver block 28 having a top plate 29 and carried by a sleeved plunger 30 slidably engaged with the plunger 24 is provided with drivers 31. Leading from a suitable nail feeding mechanism are tubes 32. In some respects the nail guide block 23 and the driver block 28 with its drivers and the nail supply tubes 32 are substantially the same in structure and operation as explained in Letters 40 Patent No. 591,366, granted Oct. 5, 1897, on application of H. W. Winter. So far as the present invention is concerned, however, the nails might be supplied by hand and the placing of the nail driving mechanism in 45 proper position relatively to the last, and the operation of such mechanism might be effected by hand.

In operation, the shoe is placed in proper 50 relationship with a heel which latter may

be mounted upon a suitable support indicated at 33 in Fig. 3, and the cone section 16 swung up to the position shown in said Fig. 3. Then, either by raising the shoe and heel and the support of the latter into proper 55 position relatively to the nail supplying and driving mechanism, or by passing the nail supplying and driving mechanism down into the heel portion of the shoe past the tilted up cone section 16, the parts of the 60 supplying and nailing mechanism will be caused to assume the relationship indicated in Fig. 4. Nails are then supplied through the tubes 32 so that they slide down through the throats 26 in block 23 and into the nail 65 holes 22 in the heel section 15 of the last, the points of the nails then simply bearing upon the insole. Then the sleeve 30 is actuated so as to depress the driver block 28 (or the other parts might be elevated) so that 70 the drivers 31 will force the nails into the heel as indicated in Fig. 3.

After this operation, the members of the nailing mechanism above section 15 are removed from the position shown in Fig. 3 75 and the cone 16 then swung back to the position shown in Fig. 1 and subsequent operations are then performed upon the shoe.

It will now be understood that the section 80 15 of the last not only serves as means for 85 permanently holding the upper of the shoe under lasting tension without interruption during the heelng operation, but also temporarily constitutes the nail block or holder of a nailing mechanism. Moreover, said 90 section 15, being the lower and wider section of the heel part of the last, enables the nail pockets to be so close to the outer margin thereof as to drive the nails through the 95 inturned heel seat margin of the shoe upper. 100

It will be readily understood that if desired, after the completion of the shoe, the last may be removed by first swinging up the cone section 16 and then swinging up the lower section 15, both swinging upon the 105 same pivotal point 13, thereby reducing the frictional resistance of such movement to substantially one-half of what would be required if the heel part of the last were not divided substantially as illustrated and 110 described.

Having now described my invention, I claim:—

1. In an apparatus of the class described, nail supplying and guiding means, nail driving means, and a last having a heel part provided with holes corresponding to the guiding means, and interfitting means between the heel part and the said means whereby the parts are held in proper operative relation during the driving of nails through the heel part. 120

2. A last having a heel section provided with nail holes, said section being constructed and arranged to provide the nail block 125

130

of a heel nailing machine and having means for insuring alinement of its nail holes with the nail supplying elements of said machine.

3. A last having a heel section provided with a series of nail holes in relative positions to direct nails driven therefrom through the heel seat margin of the upper, and having a cone section movably mounted above the first-mentioned section.

10 4. A last having hingedly connected fore and heel parts, the heel part comprising superimposed individually hinged sections.

5 5. A last comprising a forepart and a plurality of superimposed heel sections individually hinged in alinement to the forepart.

15 6. A last comprising a forepart and a plurality of superimposed heel sections, the upper heel section being displaceable and the lower heel section having nail guiding holes.

20 7. A last comprising a forepart and a

horizontally divided heel part hinged thereto, the lower section of the heel part having nail apertures.

25 8. A last having a forepart and a heel part comprising upper and lower sections both of which are hinged to the forepart, said two sections having interengageable means to prevent relative lateral displacement.

30 9. A last having a forepart and a heel part comprising upper and lower sections both of which are hinged to the forepart, said two sections having interengageable means to prevent relative lateral displacement, the lower heel section having nail apertures.

35 10. A last comprising a forepart and two superimposed heel parts, each of the latter having a lug, and a pivot pin passing through said lugs and mounted in the forepart.

In testimony whereof I have signed my name to this specification.

CHESTER HUNT.
